UNITED STATES PATENT OFFICE.

THOMAS E. REDDY, OF PITTSBURG, PENNSYLVANIA, ASSIGNOR TO GEORGE C. ERDNER, OF BELLEVUE, PENNSYLVANIA.

METHOD OF MAKING SHOT.

No. 857,756.

Specification of Letters Patent.

Patented June 25, 1907.

Application filed August 29, 1906. Serial No. 332,443.

To all whom it may concern:
Be it known that I, THOMAS E. REDDY, a citizen of the United States, residing at Pittsburgh, in the county of Allegheny and State of Pennsylvania, have invented certain new and useful Improvements in Methods and Apparatus for Making Shot; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improved method of manufacturing shot, and it comprises the dropping of the molten lead from the bottom of the kettle into a moving body of plumbago, commercially known as "East India graphite," and the invention further consists of a suitable apparatus for the making of shot in accordance with my improved method, as will be fully described herein-after.

In the accompanying drawings:—Figure 1 is a side section, partly in elevation, of a complete apparatus for the manufacture of shot in accordance with my improved method. Fig. 2 is an enlarged sectional elevation of a portion of the bottom of the shot kettle, showing the perforations of the same, together with a portion of the removable perforated distributing plate. Fig. 3 is a plan view of the same.

To construct an apparatus for the manufacture of shot in accordance with my invention, I first provide a melting kettle 6, which I prefer to arrange in connection with a heater for the purpose of melting and maintaining the lead therein at a certain temperature. This heater comprises an annular shell 2, having air openings at the base and open at the top for the reception of the melting kettle 6, said kettle being supported therein by means of a circumferential integral flange 7 formed about the same. Arranged within the interior of the shell 2 is a gas burner 3, which is fitted with a gas-supply pipe, in which is an air mixer 4 and regulating valve 5. Connected to the bottom of the melting kettle 6 is a drain pipe 8, fitted with a stop valve 9, the discharge end of said pipe being arranged over a suitably formed

drop-kettle 10. This drop kettle consists of a cast iron receptacle having a series of circumferential shallow grooves 15 formed in the bottom, and each groove having a series of minute openings 16 extending through the said bottom. Resting on the side walls of the receptacle 10, slightly above the plane of the bottom 14, is a perforated disk 12, said perforations being arranged in circles intermediate of the grooves 15 of the bottom 14, in such manner that the perforations 13 of the disk will not be immediately above the perforations and grooves 15 of the bottom 14.

Arranged beneath the shot kettle, above described, is a large receptacle 18, capable of containing a quantity of plumbago in pulverized form. This receptacle 18 tapers to a small cylindrical chamber 20 at the bottom, and the said chamber separated from the upper part by a slide valve 21, which may be opened or closed, as desired. Attached to the base of the chamber 20 is a downwardly extending shaft 29, loosely mounted in a stand 28 firmly fixed to the floor, in such manner that said shaft and its connected receptacle may be free to revolve. To provide a means for revolving the receptacle 18, a bevel wheel 25 is attached to the shaft 29, the said bevel wheel being in mesh with a pinion 26, mounted on a drive-shaft, said shaft being supported in a bearing and driven by a band wheel 27. The side walls of the chamber 20 are formed with a series of openings 22, and loosely arranged about the exterior of said chamber is a casing 23, which casing is fitted with a spout 24, the discharge end of which is arranged over a bin 30.

In operation, the lead used in the manufacture of the shot is suitably tempered or hardened by arsenic and reduced to a molten condition in the melting kettle 6, and a suitable quantity transferred to the drop kettle 10 through the medium of the pipe 8. The molten metal percolating through the perforations 13, spreads to the grooves 15 in the bottom of said kettle and through the perforations 16, collecting about the lower perimeter of said openings in small globular form until it drops into the plumbago 19 below. This body of plumbago 19 is kept in constant motion by the band wheel 27, which movement will prevent the one shot from falling upon the other before sufficient time has lapsed to permit the metal to harden by

diminished temperature. The shot thus made may be removed by opening the slide valve 21 and permitting the same to escape through the spout 24.

In practice, it has been found that shot manufactured by this method do not flatten or explode when dropped into a mass of plumbago but keep their spherical form.

The advantages of this method of making shot over those now in common use, is the inexpensive apparatus, compared with high shot towers, &c., well known in the art.

Various slight modifications and changes may be made in the apparatus without departing from the spirit of the invention. Therefore I do not wish to confine myself to that shown and described.

Having thus described my invention, what I claim, and desire to secure by Letters Patent, is:—

1. The herein described method of manu-

facturing shot, which consists in discharging molten lead in globular form into a body of plumbago.

2. The herein described method of manufacturing shot, which consists in discharging molten lead in globular form into a body of plumbago or graphite, said body of graphite being in constant motion to prevent one globular particle from falling upon the other. 25

3. The herein described method of manufacturing shot, which consists in discharging molten lead in globular form into a body of graphite having a constant rotary motion, as described. 30

In testimony whereof, I affix my signature, in presence of two witnesses.

THOMAS E. REDDY.
